ION TRAP GUN

David Dale Van Ormer, Lancaster, Pa., assignor
to Radio Corporation of America, a corporation
of Delaware

Application November 7, 1951, Serial No. 255,186

10 Claims. (Cl. 313—70)

1
This invention is directed to cathode ray tubes and specifically to gun structures for such tubes incorporating structure for trapping negative ions in the cathode ray beam.

In cathode ray tubes utilizing a single electron gun, various expedients have been used for trapping negative ions in the electron beam. It is believed that such negative ions originate in or near the cathode surface of the electron gun, and are directed and accelerated with the electron beam toward the fluorescent screen of the cathode ray tube. Continual bombardment of the fluorescent screen by these heavy negative ion particles has resulted in a darkening of the screen near its center, which is attributed to a decomposition or "burning" of the phosphor material constituting the fluorescent screen. To eliminate such screen burning, arrangements of electrode structure between the cathode electrode and the fluorescent screen have been used to provide a trapping device or means to prevent the heavy negative ion particles from reaching the fluorescent screen of the tube.

This invention is directed to cathode ray tubes of the type having an electron gun structure for forming a plurality of electron beams which are focused and brought to convergence on the fluorescent screen of the tube by a magnetic lens field. Such multiple beam gun structures may be used in cathode ray tubes in which the multiple beams are brought to a common point of convergence at the fluorescent screen by a magnetic focusing coil. Such applications find use in projection-type cathode ray tubes, in which an intensely brilliant picture is desired for projection upon a screen. Also such plural beam guns find use in color television reception, in which it is necessary to separately modulate each beam with a different color signal. Such an application is disclosed in the co-pending application of H. C. Moody, Serial No. 166,416, filed June 6, 1950. In such applications it is desirable that the heavy negative ion particles which constitute a portion of the electron beam be eliminated from the beam before it strikes the phosphor screen.

It is therefore a purpose of this invention to provide a negative ion trap structure for a plural beam electron gun.

It is a further object of this invention to provide a simple ion trap structure for a plurality of electron beams directed toward a fluorescent screen.

It is another object of this invention to provide a method of completely separating the negative ions in a plurality of electron beams by utilizing

the electron gun structure of a cathode ray tube.

It is a further object of the invention to provide a method of trapping negative ions in a plurality of electron beams with the use of the 5 magnetic lens which focuses and converges the electron beams at the fluorescent screen.

The invention is to a multiple beam cathode ray tube using an ion trap to prevent screen burning, during tube operation. The invention 10 utilizes the magnetic focusing and converging coil together with gun electrode trapping structure for preventing the negative ions in each beam from striking the fluorescent screen. The gun electrode trapping structure comprises an 15 opaque electrode barrier structure positioned in the path of each of the electron beams which blocks or traps the negative ions in each beam. A focusing coil is used for deflecting or directing the electrons of each beam away from the blocking barrier structure. Since the negative ions are little affected by the magnetic focusing field, they continue along the original beam path to strike the barrier. Modifications disclose beam diverting electrodes for directing the electron 20 beams toward the ion trap barriers, in combination with the focusing field for directing the electrons of each beam away from the ion barrier electrodes.

Fig. 1 discloses a sectional view of a plural beam cathode ray tube incorporating an ion trap 30 in accordance with the invention.

Fig. 2 discloses a partial sectional view of an alternative form of plural beam cathode ray tube having an ion trap in accordance with the invention.

Fig. 3 is a sectional view of the structure of Fig. 2 and along the sectional line 3—3.

Fig. 4 is an alternative form of a plural beam cathode ray tube utilizing an ion trap structure.

Fig. 1 discloses a cathode ray tube 10 having a tubular neck portion 12, within which is mounted an electron gun structure 14. The electron gun 14 is one, which provides a plurality of electron beams 16 directed into a bulb portion 18 of the tube envelope 10. Bulb portion 18 is closed by an end wall portion 20 having on the inner surface thereof a film of phosphor material 22 forming a luminescent screen. Electron gun structure 14 includes a plurality of cathode electrodes 24 consisting of tubular members mounted parallel to each other and symmetrically disposed about the axis of the tubular neck portion 12. The tubular cathodes are closed at the ends, closest 50 to the phosphor screen 22, by solid wall portions 55 to the phosphor screen 22, by solid wall portions

positioned to face the axis of the envelope neck 12 at an angle

Deposited on these closed ends of cathode electrodes 24 are mixtures of barium and strontium oxide coatings to form sources of the electron forming beams 16. Within the tubular cathodes 24 there are provided filamentary heater windings for maintaining the cathodes at thermionic emitting temperatures during tube operation. Enclosing the tubular cathodes 24 is a control grid 26 closed, at the end adjacent the phosphor screen 22, by a wall portion 28 having an indented portion extending parallel over the angularly disposed surfaces of the cathode electrodes 24. The wall portion 28 has apertures, overlying the coated surface of the cathode electrodes, one over each cathode surface for the passage therethrough of electrons from the activated cathode surfaces. An accelerating electrode 30 is positioned along the axis of the envelope neck 12 and closely spaced from the control electrode 26. Accelerating electrode 30 is closed by a centrally apertured wall portion 32 having the portion surrounding the central aperture extending into the indented portion of the control grid wall 28, as shown. The specific electron gun structure described, is disclosed in greater detail in the co-pending application of D. D. Van Ormer, Serial No. 248,357, filed September 26, 1951. This invention is not directed to the specific gun structure disclosed in the co-pending application, but the gun structure is merely described as illustrative of one providing a plurality of electron beams 16.

The gun structure 14 also includes a second accelerating electrode 33 spaced along the axis of envelope neck 12 and between the screen 22 and accelerating electrode 30. The portion of the inner surface of the tube envelope 10 between accelerating electrode 33 and the fluorescent screen 22 is coated with a conductive coating 34 such as carbon, which is conductively connected to accelerating electrode 33 by spring spacer fingers 36. The electrons emitted by cathodes 24 are urged through the apertures of control grid portion 28 by the accelerating field of electrode 30. The electrons passing through each control grid aperture form a beam which converges to a first crossover point on the axis of the tube neck portion 12. The design and arrangement of the gun structure is such that the crossover points of each electron beam will coincide in a restricted region 38 beyond which the beams 16 will appear to diverge from each other and from the common crossover point 38. A magnetic focusing field is provided, by a focusing coil 40 having a metal casing 42 providing the flux path of the field of coil 40. Focusing coil 40 is mounted on the tube neck 12, so that the focusing field formed is coaxial with the tube. Furthermore, the coil 40 is positioned so that the field of the coil will converge all electrons issuing from the common crossover point 38 to a common point on the fluorescent screen 22. The focusing coil 40, as described in greater detail in the above cited co-pending application of Van Ormer, also brings the electrons within each beam into sharp focus at the convergence point on the screen. This is schematically shown by the dotted beam paths illustrated in Fig. 1.

There are formed, either in the cathode-emitting surface or adjacent to the cathode-emitting surfaces, negative ions, which may be of oxygen or of other material. Because of their negative charge these ions are accelerated down the tube

axis in the same manner as are the negative beam electrons. Due to their heavy mass, these negative ions will strike the fluorescent screen 22 with sufficient energies to damage or burn the screen. The effect of negative ion bombardment on the fluorescent screen is the formation, after a period of time, of a brown or burned area where the ions strike. To prevent the negative ions in the electron beams from passing to the fluorescent screen 22, the accelerating electrode 33 is provided with a limiting apertured barrier wall portion 37 which is positioned in the paths of the electron beams diverging from the common crossover point 38. When the electron beams are converged by the field of focusing coil 40, the barrier wall 37 will effectively block the negative ions as they are not affected by the focusing field.

The voltages disclosed in Fig. 1, as being applied to the several electrodes, are not limiting but illustrate the conditions under which a tube of the type disclosed in Fig. 1 may be successfully operated. To adjust the voltages so that the ion trap is effective, the magnetic focusing field of coil 40 is first set at zero. The voltage of accelerating electrode 30 is then raised until the beams leaving the common crossover point 38 are sufficiently divergent that they are completely cut off from the fluorescent screen 22 by the barrier aperture 37. This, then assures that the ions within the beam will also be cut off by the ion trap portions 37. The current in the focusing coil is now increased until the electron beams appear on the screen and are brought together to the point of common convergence and focus. Since the negative ions of the beam are not affected by the field of focusing coil 40, they are effectively blocked by the opaque ion trap barrier 37. The electron beams may now be scanned over the fluorescent screen 22 in any well-known manner, as by magnetic deflecting fields provided by two pairs of deflecting coils mounted, as is shown, in a yoke structure 44. The construction of the scanning yoke 44 and its mode of operation for scanning the beam over the screen surface may be conventional and is not described in further detail.

Figures 2 and 3 disclose an alternative form of plural beam electron gun structure consisting of a plurality of parallel electron guns, each having a tubular cathode 46, a control grid 48, first accelerating electrodes 50, and second accelerating electrodes 52. Electrodes 48, 50, and 52 may be tied electrically to their corresponding part in the other electron guns. The electron beams of the tube may be separately modulated by applying independent signal voltages between each cathode 46 and its respective control grid 48. Electrons from the cathodes 46 are formed, as is schematically shown, into electron beams 53 which pass through accelerating electrodes 52 into a focusing electrode 54 maintained at a higher positive potential than the accelerating electrodes 52. Spaced beyond focusing electrode 54 is a third accelerating electrode 56 tied electrically to a conductive wall coating 58, corresponding to coating 34 of Fig. 1. Accelerating electrode 56 is maintained at a higher positive potential than electrode 54.

Focusing electrode 54 has a plurality of short tubular elements 60 aligned with each of the electron guns and provides with the adjacent portion of accelerating electrodes 52 a focusing field for contributing to each beam a converging or partial focusing effect. A common magnetic

focusing and beam converging field is established by a focusing coil 62. The field of coil 62, as disclosed in Fig. 1, brings the electron beams 53 to a common point of convergence and beam focus at the fluorescent screen of the tube. The third accelerating electrode 56 is formed with an apertured wall portion 64, out of alignment with the electron beam paths 53.

The potentials indicated in Fig. 2 are illustrative of those which may be applied for tube operation. The adjustment of the electrode potentials of the tube are made as follows. With the current of coil 62 set at zero, the potential of electrodes 54 and 56 are made equal. The electron beams then issuing from focusing electrode 54 will pass down the tube and clear the electrode wall 64. The potential of the accelerating electrode 56 is then made more positive relative to the potential of focusing electrode 54 to cause the beams to diverge outwardly from the tube axis. The potential of electrode 56 is raised until the beams are completely cut off by the electrode wall portion 64 and no portion of the beam passes through the aperture. This also effectively prevents the negative ions in the beams 53 from striking the fluorescent screen of the tube. The current in the magnetic focusing coil 62 is then increased until the beams converge to clear the apertured wall portion 64. The convergence of the beams is continued until they are brought to a common point on the screen, after which the beams may be used in any manner desired. Because of the magnetic convergence of the beams by coil 62, the negative ions in the beams are little affected and continue to be trapped by the apertured wall portion 64 of accelerating electrode 56.

Fig. 4 discloses an alternative form of the gun structure shown in Fig. 2. The accelerating electrodes 54 and 56 in Fig. 2 are combined into a common accelerating electrode 65 having an apertured wall portion 66 at the end closest to the fluorescent screen of the tube. Accelerating electrode 65 is tied by spring fingers 68 to the conductive wall portion 70, which extends to a point adjacent to the fluorescent screen. The electron beams, in the manner described for Fig. 2, enter accelerating electrode 65 substantially along parallel paths symmetrically arranged about the tube axis. The aperture in the electrode wall 66 is smaller than that in the ion blocking wall 64 of Fig. 2. In combining electrodes 54 and 56 of Fig. 2 into a single electrode 65, the divergent action of electrodes 54 and 56 on the electron beams is eliminated. In order that the electrode structure 66 of Fig. 4 effectively trap the negative ions the electrode wall 66 must effectively block the parallel beam paths entering the electrode 65. The magnetic coil 72 is used to converge the electron beams so that they pass through the central aperture in plate 66 while the negative ions of the beam continue on and strike wall 66.

While certain specific embodiments have been illustrated and described, it will be understood that various changes and modifications may be made therein without departing from the spirit and scope of the invention.

What is claimed is:

1. An electron discharge device comprising electrode gun means for providing a plurality of electron beams along respective paths, said electron gun means including an accelerating electrode having an electron impermeable portion thereof positioned in the path of each elec-

tron beam and an aperture therethrough, means for producing a magnetic focusing field for directing said beams from their respective beam paths through the aperture of said accelerating electrode.

2. An electron discharge device comprising a plurality of electron guns symmetrically arranged about an axis for providing a plurality of electron beams along respective paths, an accelerating electrode common to said electron guns having an electron impermeable portion thereof positioned in the path of each electron beam, said accelerating electrode having an aperture therethrough surrounding said axis, and a magnetic field producing means for directing said beams from their respective beam paths through said accelerating electrode aperture.

3. An electron discharge device comprising electron gun means including a plurality of apertured electrodes coaxially spaced along a common axis and a plurality of cathode electrodes symmetrically spaced about said axis for providing a plurality of electron beams along respective paths, said electron gun means including an accelerating electrode having an electron impermeable portion thereof positioned in the path of each electron beam, said accelerating electrode having an aperture therethrough surrounding said axis, and a magnetic field producing means for directing said beams from their respective beam paths through said accelerating electrode aperture.

4. An electron discharge device comprising a plurality of electron guns arranged parallel to each other and symmetrically spaced about an axis for providing a plurality of electron beams along parallel paths, an accelerating electrode common to said electron guns having an electron impermeable portion thereof positioned in the path of each electron beam, said accelerating electrode having an aperture therethrough surrounding said axis, and a magnetic field producing means for directing said beams from their respective beam paths through said accelerating electrode aperture.

5. An electron discharge device comprising a plurality of electrodes and an electron source symmetrically arranged about an axis for providing a plurality of electron beams along respective paths, a pair of accelerating electrodes spaced along and surrounding said beam paths from said electrodes, lead means connected to said accelerating electrodes for applying different potentials to said accelerating electrodes to form an electrostatic field therebetween for changing the direction of said electron beams along divergent paths, said accelerating electrode positioned farther from said electrodes having an electron impermeable portion thereof positioned in the divergent path of each electron beam, said accelerating electrode having an aperture therethrough surrounding said axis, and a magnetic field producing means for directing said beams from their respective beam paths through said accelerating electrode aperture.

6. An electron gun structure for providing a plurality of electron beams along respective paths, said structure comprising, a plurality of electron emitting cathode portions directed toward a common axis, an accelerating electrode having an aperture therethrough surrounding said axis, and a control grid electrode portion positioned between each of said cathode portions and said accelerating electrode, said control grid portions each having an aperture there-

through, said accelerating electrode having an electron impermeable portion thereof positioned in the path of each electron beam.

7. An electron gun structure for providing a plurality of electron beams along respective paths, said structure comprising, a plurality of cathode electrodes each having an electron emitting surface positioned at an angle facing a common axis, a common tubular accelerating electrode spaced from said cathode electrodes coaxially with said common axis, and a common control grid electrode spaced between said cathode electrodes and said accelerating electrode, said control grid electrode having an apertured portion overlying each of said electron emitting cathode surfaces and between said emitting surfaces and said common axis, said accelerating electrode having an electron impermeable portion thereof positioned in the path of each electron beam.

8. An electron gun structure comprising, electron gun means for providing a plurality of electron beams along parallel paths and symmetrically disposed about an axis, an accelerating electrode having an aperture surrounding said axis and an electron impermeable portion thereof positioned in the path of each electron beam.

9. An electron discharge device comprising, electron gun means including a source of electrons for providing a plurality of electron beams along parallel paths, a common accelerating

electrode having an aperture therethrough surrounding said beam paths, said accelerating electrode including an electron impermeable wall portion, means for directing said electron beams toward said impermeable wall portion, and a magnetic coil surrounding said beam paths for providing a converging magnetic field redirecting said electron beams through said accelerating electrode aperture.

10. A cathode ray tube comprising, electron gun means for providing a plurality of electron beams along paths symmetrically disposed about a common axis, said electron gun means including an accelerating electrode surrounding said beam paths, said accelerating electrode having an electron impermeable portion thereof positioned in the path of each electron beam and an aperture therethrough on said axis, means for producing a magnetic focusing and deflecting field for directing said beams from their said respective beam paths through the aperture of said accelerating electrode.
